UNITED STATES PATENT OFFICE.

FRANK WILCOMB, OF NORRISTOWN, PENNSYLVANIA, ASSIGNOR TO HEMPHILL MANUFACTURING COMPANY, OF CENTRAL FALLS, RHODE ISLAND, A CORPORATION OF RHODE ISLAND.

SPRING-NEEDLE KNITTING-MACHINE.

1,244,674.

Specification of Letters Patent. Patented Oct. 30, 1917.

Application filed January 9, 1915, Serial No. 1,386. Renewed March 21, 1917. Serial No. 156,454.

To all whom it may concern:

Be it known that I, FRANK WILCOMB, citizen of the United States, residing at Norristown, Pennsylvania, have invented certain new and useful Improvements in Spring-Needle Knitting-Machines, of which the following is a specification.

My invention relates in the main to spring needle stocking knitting machines, in which 10 a needle cylinder and cams have relative rotary and reciprocatory movements, though it will be understood that all features of my invention are not confined to machines of this general type.

For instance, some of the features may be used in an underwear machine where there is no reciprocatory movement, or straight bar 15 knitting machines.

The invention consists in the features and 20 combination of parts hereinafter described and particularly pointed out in the claims.

In the drawings—

Figure 1 is a view of the knitting elements at the position of the yarn feed mouth, the 25 presser bits being retired;

Fig. 2 shows the needle partly retracted;

Fig. 3 shows the pressing of the needle beards;

Fig. 4 shows the measuring of the new 30 loops across the tops of the web holders previous to drawing into the fabric;

Fig. 4a is a view similar to Fig. 4 with the web holders retracted and the measured loops ready to be drawn into the fabric;

Fig. 5 shows drawing the measured new 35 loop into the fabric;

Fig. 6 is a diagrammatic view looking from inside the needle row outwardly showing the measuring off of the new loops previous to being drawn into the fabric;

Fig. 7 is a view showing how the inoperative needles are utilized to prevent the surplus yarn from being caught under the nib of the web holder in reversing the direction 45 of rotation of the machine in making heels and toes;

Fig. 8 is a plan view of the knitting head;

Fig. 9 is a vertical sectional view of the knitting head;

Fig. 10 is a plan view of a modified form of yarn holder or feeder ring and the beard pressers;

Fig. 11 is a sectional view of Fig. 10;

Fig. 12 is a sectional view of a modified

form of the yarn holder or feeder and beard presser showing inserted feeder teeth or projections;

Fig. 13 is a further sectional view taken through the solid part of the ring of Fig. 12;

Fig. 14 is a view of the web holder out- 60 throw cam;

Fig. 15 is a developed view of the cams for the needles and web holders.

In Letters Patent of the United States granted to me September 16, 1914, #1073309, 65 I disclose sinkers for feeding the yarn to the needles in the ordinary way, and web holders having nibs across the tops of which the loops measured off by the sinkers are evened up before being drawn into the 70 fabric. In machines built in accordance with said patent the sinker formed stitches as they drop from the sinker ends lose their shape to some extent while passing down across the space, occupied by the pressing 75 and needle evening means, to the web holders, and these distorted loops are leveled or evened up across the tops of the web holder nibs.

In my present invention the measuring off 80 of the loops previous to being drawn into the fabric is accomplished by the conjoint action of the needles and web holders, the sinkers being omitted and the feeding of the yarn being done directly to the needles and 85 across the tops of the web holder nibs which perform the precise function of the sinkers, needles and web holders of my previous patent in so far that a series of new loops are completely measured off previous to drawing 90 the newly formed loops into the body of the fabric.

So far as the feeding of the yarn to spring 95 bearded needles is concerned, it may be pointed out that when sinkers are employed the yarn is sunk between the needles below the beards and held taut across the stems while the needles are being retracted until the beard is below the line of the sunken taut loops, thus insuring that the needle 100 takes the yarn without splitting it.

When latch needles are employed, the latches in closing throw the yarn under the hooks of the needles, and no other provision is needed to insure the taking of the yarn 105 by the hooks.

It is true that spring beard needles may be supplied with yarn direct, *i. e.*, without

sinkers, and each needle draw its own loop directly into the fabric, without previous measuring, in the same manner as with latch needles, but in this case the loop formation is open to the objections of latch needle knitting and the fabric produced is not equal in quality or appearance to true spring needle knitting where each new loop is measured in advance of casting off the old loop, and is drawn into the fabric without rendering from needle to needle.

By my invention, while sinkers are not employed, but direct feeding of the needles is used instead, I am still able to get the results of true spring needle knitting in that each loop side is equal in length to all others, and the measured loop, when drawn into the fabric, is precisely the same in form and relation to other loops as in true spring needle knitting where sinkers are employed, and in which rendering of the yarn from needle to needle is avoided while drawing the new formed loops into the fabric.

The difficulty of feeding successfully independently operated spring needles direct is fully appreciated by knitters, and various suggestions have been made to meet the difficulties, an example of which is illustrated in Letters Patent of the United States granted to Clay, 40993 of 1862; J. Hollen, 11,995, November 28, 1854; 25,827, October 18, 1859, and the feeder 14 shown in patent of T. Fowler, 13,165, July 3, 1855, and also the patent to Crane, 1,027,034, May 21, 1912, it being understood that independently operated direct fed spring needles were old and common prior to the use of latch needles and later.

In my present machine where the bearded needles are fed direct, I employ stationary means outside the needle row to hold the yarn, or feed it close against the needle stem without sinking it between the needles so that the needle beards will be sure to seize it on their downward travel, and for this purpose I employ a ring of fixed projections or teeth exterior to the needle circle, these being located close to and alternating in position with relation to the needle stems but allowing the yarn to run freely between their inner ends and the said stems, the spaces between the teeth being deep enough to allow the needle beards to travel through in their up and down movement without pressing the beards. In the spaces between these teeth are pressing means which may be either movable or fixed, in the latter case a presser device being used within the needle row to force the needles outwardly at the pressing point against the external presser means to close the beard in the same manner as in the solid ring presser shown in Letters Patent of the United States granted to me July 18, 1899, #629,116.

The spring beard needles slide vertically in grooves in the cylinder, being operated by cams in the usual way. The sliding web holders 1 are provided each with an upper nib or barb and a lower nose with a throat 70 between them, as is usual.

The external yarn feeding or holding teeth for holding the yarn against the needle stems may be of various forms and arrangement, but in Figs. 8, 10 and 11 75 I show them as formed with a ring *a*, the teeth being shown at *b*, and while this ring *a* is shown as solid in Figs. 10 and 11 with the internal yarn feeding or holding teeth *b* formed integrally therewith, the teeth 80 may be inserted in radial grooves in the ring as at *b'*, Figs. 8, 12 and 13, being held stationary in any suitable way or as shown in Figs. 12 and 13 by butts *c* on the outer ends of the tooth members entering a groove 85 at *c'*, and these bits or teeth may be of hardened steel.

In my application 831,797, April 14, 1914, I have shown a ring of similar construction, and for a similar purpose, the radial 90 grooves therein, however, holding three punchings or bits, two serving as feeders or holders for the yarn and one serving as a presser, these bits having movement, though as indicated in said application one or more 95 holders may be used for each needle. In my present invention I avoid the use of the sliding yarn feeders or holders, together with the means for operating them, and instead the fixed projections are employed, 100 thus materially simplifying the construction while maintaining efficiency in operation.

For pressing I may use various means. In the particular construction shown, I use 105 either fixed pressing means consisting of the surfaces *d*, Figs. 10 and 11, at the bottoms of the spaces between the teeth against which the beard contacts for pressing as the needle recedes, or I may use radially sliding 110 pressers *d'* shown in Figs. 1 to 8.

When the fixed form of external presser is employed, a device is used within the needle row for deflecting the needle outwardly at the pressing point to press the 115 beard and make it pass through the old loop. This inner presser device may assume various forms, but in the particular construction shown it consists of a cam-shaped member *e*, Fig. 10, which is mounted on the 120 clearer plate *f* within the needle row. This clearer plate is shown diagrammatically, and may be combined as usual with clamping means for the yarns which are out of action, and suitable cutting means for these 125 yarns may be employed. These devices may be of any suitable construction.

In some instances, as above stated, it is desirable to have movable pressers so that tuck presser wheels may be employed. 130

Such pressers may be of various forms, but I show them as sliding bits d' , Figs. 1 to 5 and Fig. 8, arranged between the teeth or projections b which feed or hold the yarn close to the stem of the needle; the presser wheel is shown at h , Fig. 8, working against the heels of the sliding pressers. When these sliding pressers are used with the external presser wheel or the external cam-shaped presser h' , Fig. 8, there may be employed within the needle row at the pressing point an evener e' , Fig. 8, which will even up any needles which may become bent, and will also act to sustain the thrust of the movable presser.

The means for directing the yarn to the knitting elements includes a feed mouth 8 having walls or edges 9 which are close to the needle stems, and inclining upwardly and outwardly, said walls or edges also diverging downwardly from each other, and between these edges at their lower ends a rest 10 for the yarn extends in close proximity to the needle stems, the inclined edges 25 serving to direct the yarn with certainty well under the needle beards when elevated to take the yarn and against the stems, and in respect to the yarn holding or feeding teeth or projections the rest is located as close as possible thereto so that the yarn will be delivered between the inner ends of these teeth and the needles, the inner ends or faces of the said projections being so close to the needles that the yarn extending across 30 these inner faces will be fed or held thereby close against the needle stems, so that as the needle retracts to take the yarn the needle beard will be buried between the feeder teeth so that the beard can not split 35 the yarn or seize knots or bunches, which ordinarily would tend to obstruct the free 40 passage of the needle beard to grasp the yarn.

By feeding the yarn down low with the feed mouth 8, the object is to position it in the crevice between the inner end of the feeder projection b or b' as the case may be, and the stem of the needle.

It will be understood that in round and 50 round knitting only one of the inclined yarn guide edges 9 is in service, while in reciprocating knitting for making heels and toes both inclined edges 9 are utilized, the yarn being directed to the right or left 55 and being guided by one edge or the other in accordance with the direction of rotation of the needle cylinder.

Knitting operation.

60 Referring to Figs. 1 to 6, the knitting operation is as follows: The yarn is fed as shown in Fig. 1 across the inner end faces of the feeder projections and over the tops of the advanced web holders, being 65 retained by said feeder projections close

against the stems of the elevated needles. Fig. 2 shows the parts in the same position, excepting that the needle has descended and is about to take the yarn, the beard having passed part way down through the space 70 between the feeder teeth or projections and over the yarn as held by the inner faces of the feeder projections against the stem. In Fig. 3 the needle has receded to the point where pressing is done. This pressing may 75 be done as above stated by the movable presser bit d' closing the beard, or if the presser ring is used without movable presser bits the needle is deflected outwardly by the presser device e inside the needle row, 80 and the needle beard is closed by being forced into contact with the solid ring at the pressing surface d in about the same manner as shown in my Patent 629,116, of 1899, the important difference existing, how- 85 ever, that in my present improvement the yarn is held by the feeder projections against the stems while the beards bury themselves in the spaces between the teeth and outside the fed yarn. These Figs. 1 to 6, however, 90 show the use of sliding presser bits, which are moved inwardly by the presser wheel h of Fig. 8.

In Figs. 1, 2 and 3 the web holders remain in their advanced positions.

Figs. 4 and 6 illustrate the measuring of the new loop lengths across the tops of the web holders, which is the next step in my improved knitting operation.

After the pressing action takes place, the 100 continued downward movement of the needle will measure off the new loops over the tops of the web holder nibs, which web holders remain in their advanced positions. This measuring is illustrated in Figs. 4 and 105 6, it being observed that the measuring is a distinct operation from and takes place previous to the action of drawing the new loops through the old.

A number of needles are shown in Fig. 6 110 in their position for measuring the new loops across the nibs of the web holders. By this I insure the maintenance of the loop lengths, as measured, until they are drawn successively into the fabric, because 115 a resistance is interposed between the loop which is being drawn into the fabric and the thread delivery point, this resistance being due to the fact that a number of loop lengths remain across the tops of the web 120 holders and remain grasped by a plurality of needles which have retracted below the tops of the web holders. This resistance prevents the drag on the yarn coming from the yarn feed mouth from exerting its force 125 upon and straightening out the loop length which is being drawn into the fabric. After the measuring action, the web holders are retracted from the position of Fig. 4 to that of Figs. 4^a and 5, thus withdrawing them 130

4

from the measured loops which are then drawn down into the fabric by the further retraction of the needle as illustrated in the last named figure, and at the left of Fig. 6. 5 Following the drawing of the new loops into the fabric the web holders are advanced to knock over the old loop and hold the fabric against rising with the advancing needles when these are raised again, as shown in 10 Fig. 1. This completes the cycle of knitting operations.

Referring to the presser bits having their stems extending radially from their nose ends to their butts and slideable in a radially 15 grooved bed, it will be seen that this arrangement renders it readily possible to employ a presser device made up of an ordinary plain periphery presser wheel and an ordinary toothed presser wheel by which 20 tucking can be done, these wheels being adjustable relative to each other, so that either one or the other will be effective.

Another advantage of the radially sliding presser bits is that the heels or butt ends 25 are widely separated, being at a larger diameter than the needles, and a cam plate operating against the heels will have a much lower angle than if located nearer the needle circle, thus adding to the effectiveness 30 and life of the parts.

The web holder bed 16 is supported on the needle cylinder, being held by the screw 17, Fig. 9, in the usual way. The web holders slide in grooves in this bed, and in grooves 35 in the top of the needle cylinder or in a ring 18 fixed thereto. The web holders, therefore, act as driving dogs to impart the rotary movement of the needle cylinder to the yarn feeder and presser ring or bed, the 40 underside of the feeder and presser bed or ring being grooved at α to receive the web holders which slide therein.

These beds for the web holder and presser 45 bits rotate within an outer ring 19 which is fixed to a standard 20 by the screw 21, Fig. 9. This outer ring has attached thereto the push cams 22, 22, Fig. 8, for advancing the web holders inwardly to the position for 50 knocking off the old loops and engaging the fabric to hold it against rising with the needles. These cams consist of arms pivotally mounted for adjustment at 23 to the outer cam ring. The push cams will be held in any adjusted position by the set or pinch 55 screw 24.

The inner cam ring 25 for the web holders has the outthrow cams 26, Figs. 8 and 14, for retracting the web holders as shown in Fig. 5 to permit the new loops which have 60 been measured off to be drawn into the fabric. This inner cam ring is held or controlled as to its circumferential position by a pin 27, Figs. 9 and 14, on the inner cam ring engaging an opening 28 in the fixed 65 outer cam ring 19. The cam ring 4 for the

presser bits overlies the said bits, and is secured in any suitable way to the outer cam ring 19.

The advantage of my two-part construction of web holder cam ring lies mainly in 70 the convenience of assembling or dismantling this part of the machine. Ordinarily it requires care and time to make the web holder butts aline with their cam path when this is formed on the under side of a single 75 cam ring. This objection is overcome with my construction as the inner cam ring with its cams is simply dropped into place on top of the web holder bed and within the circle of the web holder butts, and these 80 butts are then pushed up against the cam, thus making them assume proper positions to aline with the cams of the outer cam ring which may then be readily placed in position.

When the heel and toe pockets are made the instep needles are made inoperative in an elevated position higher than the highest position of the needles in knitting, which is ordinary practice, and during narrowing additional needles are elevated by picking in the ordinary way. As the cylinder reciprocates for narrowing and widening, the 90 yarn extending from the last needle in knitting to the thread carrier or mouthpiece must be taken up by a take-up sweep in the ordinary way. As the yarn lies so low, it is liable to drop below the web holder nibs when the web holders retract to permit new loops to be drawn into the fabric, and as the 95 web holders then advance to knock over loops and engage the fabric these strands of yarn would be caught in the throats of the web holders, preventing the take-up sweeps from taking up this surplus yarn on the opposite reciprocation of the cylinder unless 100 means are provided to prevent it.

My means consists of an interiorly arranged pair of push plates 30, Figs. 7 and 8, situated adjacent to the web holder reTRACTING cams, but nearly in radial alinement with the withdrawal part 26, Fig. 8, of the web holder cam. This push plate does not come in contact with any of the needles in knitting, as the operative needles are retracted below the plane of these push plates, but all the elevated inoperative instep needles are pushed out of their vertical plane and force the strand of yarn onto the nib of the web holders as they pass this 110 point, as shown in Fig. 7, and effectually prevent the yarn being drawn below the nibs and into the throats of the web holders. Thus a free take-up of the yarn is permitted 115 on the return stroke of the knitting. These two push plates are radially adjustable, inside the needle row, and are also adjustable circumferentially.

Fig. 7 illustrates the action just described, the elevated inoperative needle being shown 120

in full lines pushed out from the normal needle circle indicated by the needle shown in dotted lines, and it will be seen that the yarn running from the mouth piece 8 to the last needle in knitting—see the retracted or lowered needle—will be held by the deflected inoperative needle on top of the web holder nib so that as the cylinder reverses its stroke this yarn can be taken up by the take-up sweep, which it could not do had the yarn lodged beneath the nib and in the throat of the web holder.

From Fig. 15 it will be seen that the needle cams comprise a loop measuring cam 31 and a stitch cam 32, and the relation of these cams to the web holder cam path and particularly the retracting cam 26 will be clear from this developed view of these cams.

As in my Patent No. 1,131,583, March 9, 1915, the two stitch cams may have, during reciprocating knitting, a back and forth adjustment along the needle stems, and in respect to each other in opposite directions, and it will of course be understood that the various cams above described are employed in duplicate sets, one for knitting in one direction and the other for knitting in the other direction. This is true also of the evener means, the push plates 30, and presser means, and as shown and described previously the mouth piece is constructed to deliver the yarns for either direction of knitting.

The instep cam for making one set of needles inoperative in an elevated plane is indicated at 33, Fig. 15. Beard pressing means other than the kind described and shown herein can be used with the yarn feeding and holding projections, and I do not limit myself in this respect.

Some of the subject matter disclosed herein but not claimed will be embodied in a divisional application.

I claim as my invention:—

1. In combination in a spring needle knitting machine, independently operated spring beard needles, means for feeding the yarn directly to the needle stems comprising yarn delivery means and a support having a row of stationary yarn feed projections outside the needle row to hold the yarn against the needle stems below the beards without sinking the yarn between the needles, said yarn feed projections having spaces between them for the free passage of the needle beards to grasp the yarn, and beard pressing means, substantially as described.

2. In combination in a spring needle knitting machine, independently operated spring beard needles, means for feeding the yarn directly to the needle stems comprising yarn delivery means and a support having a row of stationary yarn feed projections outside the needle row to hold the yarn against the needle stems below the beards without sink-

ing the yarn between the needles, said yarn feed projections having spaces between them for the free passage of the needle beards to grasp the yarn, and beard pressers in said spaces, substantially as described.

3. In combination in a circular spring needle knitting machine, independently operated spring beard needles, means for feeding yarn directly to the needle stems comprising yarn delivery means and a circular row of stationary yarn holding or feeding projections outside the needle row to hold the yarn against the stems below the beards without sinking the yarn between the needles, said yarn feed projections having spaces between them for the free passage of the needle beards to grasp the yarn, and beard pressing means, substantially as described.

4. In combination in a circular spring needle knitting machine, independently operated spring beard needles, means for feeding the yarn directly to the needles comprising yarn delivery means and a ring having a circle of yarn feed projections fixed outside the needle row to hold the yarn close to the needle stems below their beards without sinking the yarn between the needles, said projections having spaces between them for the free passage of the needle beards to grasp the yarn and beard pressers external to the needle circle arranged in said spaces between said projections, substantially as described.

5. In combination in a spring needle knitting machine, independently operated spring beard needles, means for feeding the yarn directly to the stems thereof comprising yarn delivery means and a ring having a row of yarn feed projections to hold the yarn close to the needle stems and below the beards without sinking the yarn between the needles, and with the spaces between the projections for the free passage of the needle beards to grasp the yarn, beard pressers external to the needle circle movably mounted in said spaces between said projections, and means for operating said beard pressers, substantially as described.

6. In combination in a spring needle knitting machine, independently operated spring beard needles, a ring surrounding the same having fixed projections to hold the yarn close to the needle stems below the beards and with spaces between them to receive the needle beards, a yarn guide having a yarn support or ledge close to the needle stems and close to the top edges of the said projections for directing the yarn between the inner faces of said projections and the needle stems, and presser means for the needle beards, substantially as described.

7. In combination in a spring needle stocking knitting machine, a rotary needle cylinder, independently operated spring

 beard needles, a ring surrounding the same having fixed projections to hold the yarn close to the needle stems and with spaces between them to receive the needle beards, 5 a yarn guiding mouth having downwardly diverging guiding edges with a yarn supporting ledge at the lower ends thereof close to the needle stems and to the tops of the said projections for directing the yarn 10 across the inner faces of said projections and against the needle stem, and pressing means, substantially as described.

8. In combination in a circular knitting machine, individually operated spring beard needles, a row of fixed teeth or projections 15 outside the needle row in line with the spaces between the needles, means for feeding the yarn directly across the inner faces of the said projections without sinking the 20 yarn between the needles, pressing means on the outside of the needle row adjacent said fixed teeth, said spaces receiving the beards of the descending needles in taking the yarn and in pressing, and means within the needle row to bear on the needle stems, substantially as described.

9. In combination in a circular knitting machine, independently operated spring beard needles, an outer row of projections

in line radially with the spaces between the needles, means for delivering the yarn across the inner faces of the projections and against the needle stems, presser means, web holders individually operated, and means for operating the needles to first measure off the new loop lengths across the tops of and between the advanced web holders without drawing the new loops into the fabric and then retracting the web holders and drawing said measured new loops into the fabric 40 by the further movement of the needles, substantially as described.

10. In combination spring beard needles, a ring surrounding the needle row having inserted projections fixed thereto and extending close to the needle stems to feed the yarn onto said stems below the beards without sinking the yarn between the needles, and with spaces between said fixed projections to receive the needle beards in taking 50 the yarn, and pressing means external to the needle row, substantially as described.

In testimony whereof I affix my signature in presence of two witnesses.

FRANK WILCOMB.
